UNITED STATES PATENT OFFICE.

GEORGE H. WARTMAN, OF MONTESANO, WASHINGTON TERRITORY.

SMOKING-PIPE.

SPECIFICATION forming part of Letters Patent No. 392,768, dated November 13, 1888.

Application filed December 16, 1887. Serial No. 258,061. (No model.)

To all whom it may concern:

Be it known that I, GEORGE H. WARTMAN, of Montesano, in the county of Chehalis and Territory of Washington, have invented a new 5 and Improved Smoking-Pipe, of which the following is a full, clear, and exact description.

My invention relates to an improvement in smoking-pipes, and has for its object to provide a pipe wherein the nicotine will be extracted from the smoke before entering the stem and be prevented from penetrating the bowl, and wherein the smoke, upon reaching the mouth-piece, will be cool and pleasant, and dirt or sediment be prevented from settling in 10 the stem, and, further, wherein the bowl will never burn and may be colored quickly and uniformly.

The invention consists in the construction and combination of the several parts, as will 15 be hereinafter fully set forth, and pointed out in the claim.

Reference is to be had to the accompanying drawings, forming part of this specification, in which similar letters of reference indicate 20 corresponding parts in all the figures.

Figure 1 is a central longitudinal section through the bowl of the pipe. Fig. 2 is a plan view of the same with the cap removed, and Fig. 25 3 is a bottom plan view of the cap.

In carrying out the invention the bowl A of 30 the pipe, which may be made of any desired shape or material, is provided with a central receptacle, B, for tobacco or other article to be smoked, having no direct communication 35 with the aperture in the stem E'.

The receptacle B, which is located centrally 40 within the bowl, while illustrated as an integral portion thereof, may, if desired, be made removable, in which case it is secured to the bottom by a screw-thread, or in any other convenient or approved manner.

An annular chamber, D, is made to intervene 45 the inner walls of the bowl and the outer walls of the tobacco-receptacle, adapted to be ordinarily filled with cotton, or other equivalent loose fabric admitting the passage of smoke, a connection being formed between the receptacle B and the chamber D by producing one or more, preferably four, apertures, d', in 50 the side of the said receptacle leading into the said chamber, as illustrated in Fig. 1.

The integral neck E of the bowl, to which the stem E' is attached, is provided with the usual channel, e, which, however, extends but a short distance inward, being connected with 55 an annular groove, a, produced in the upper edge of the bowl proper by a tube, F, which tube is integral with said neck and the bowl, having an inlet from the groove of the latter at b, as illustrated in Figs. 1 and 2. 6c

The tobacco-receptacle B extends above the bowl, and is surrounded at that point by a rim or cap, H, which cap is provided with an annular channel, h, in the under face to receive the inner flange, b', formed in the bowl by the 65 groove a, and an exterior thread adapted to engage a similar thread cut in the outer wall of the groove a. The cap thus screwed upon the bowl or secured thereto in any other approved manner renders the chamber D virtually air-tight. A connection is, however, obtained between the said chamber and the stem of the pipe by cutting transversely in the under side of the cap a recess, k, which recess is 70 adapted to intersect the chamber D and register with the inlet b to the tube F. Thus in operation the smoke is drawn through the apertures d' into the chamber D, through the packing therein, up by means of the recess k into the inlet b, through the tube F into the 75 channel of the neck E, and from thence through the stem.

The above-described construction is particularly adapted to meerschaum bowls or bowls of other material adapted to be colored, as the 80 heated tobacco, not coming in contact with the bowl, will not and cannot burn the same. The smoke also comes cool to the mouth and free from nicotine, while the smoke passing to the stem in the manner shown prevents the latter 85 from being choked by dust or other sediments. The bowl is also rendered much stronger by the absence of the usual hole in the bottom connecting with the neck.

Having thus described my invention, what I 90 claim as new, and desire to secure by Letters Patent, is—

The herein-described pipe, consisting of the bowl A, provided with the tobacco-receptacle B, having apertures d' in its sides near the 95 bottom, the annular chamber D, surrounding the sides of the receptacle B, the annular and

screw-threaded groove *a* in the upper edge of the bowl, the tube *F* on the front of the bowl and leading to the top thereof, the neck *E*, provided with the channel *e*, extending inward a short distance beyond the tube *F*, and the screw-threaded cap *H*, provided with the annular groove *h*, forming two depending flanges fitting in the annular chamber *D* and groove

a, and the transverse recess *k*, connecting the chamber *D* with the passage *b* of the tube *F*, to as specified.

GEORGE H. WARTMAN.
